BUILDING WALL STRUCTURE

Mills G. Clark, Cleveland Heights, Ohio, assignor
to Insulated Steel Construction Company,
Cleveland, Ohio, a corporation of Ohio

Application February 8, 1933, Serial No. 655,790

5 Claims. (Cl. 189—34)

This invention relates to wall construction in metal building structures. The general objects of the invention are to provide a highly efficient wall construction of simple form, low cost and convenient erection; and to these ends, one wherein a large and more difficult part of the assembly may be made in the shop, leaving for the field work, principally only the securement together of the remaining parts.

10 The exact nature of this invention, together with further objects and advantages thereof will be apparent from the following description taken in connection with the accompanying drawing, which shows perspective views illustrating the invention, and in which Fig. 1 is a detail of one of the typical units from which the wall base is made up; Figs. 2 and 3 show wall base sections, as formed in the shop; Fig. 4 illustrates the manner of joining a pair of such sections in the field; Fig. 5 illustrates the completed wall base; Figs. 6—8 illustrate corner constructions.

With reference now to Fig. 1 the unit comprises a sheet metal strip bent lengthwise along parallel lines to form a pair of wide shallow adjacent panels opening oppositely, with the channel bottom parts 1 defining side faces for the unit, and lips 2 extending from the free channel extremities at the opposite edges of the unit. The channels have flat sides 3 and the bottoms 1 are also flat, and the parts are generally rectangularly disposed, but the sides 3 preferably have sufficient pitch to permit stacking of a plurality of similar units in nested relation. Such pitch is shown in Fig. 1 of the drawing, but in 35 the remaining figures, for simplicity, no pitch is shown.

More channels than the pair illustrated could be provided per unit, but I have found a pair preferable for commercial reasons and for convenient handling. A unit may be made from 20-gauge stock 22 inches wide with each channel 8 inches wide and 2 inches deep, leaving the lips 2 a width of about $\frac{3}{8}$ inch. Obviously from wider stock more channels of similar dimensions could be obtained per unit, but not as cheaply per channel.

From a number of such units, wall base sections are made up as illustrated, Fig. 2, the units being disposed in interlocking relation, in a common general plane, the channel bottom parts defining side faces for the section, the parts 3 forming webs between these faces and the end channel sides 3 of each unit being hooked over the corresponding part of the next unit, and the intermediate lips 2 of adjacent units being weld-

ed at intervals to the channel bottom parts which they overlie, as indicated at 4.

The length of the end webs 3 of each unit might be slightly shorter than that of the intermediate web, so that theoretically all the bottom parts 1 lying in one face of the assembled section would lie exactly in a common plane. However, such disposition is sufficiently approximated, where metal of the light gauge specified be employed, with all of the webs 3 having the same dimension. It will be appreciated that in the drawing the thickness of the metal is exaggerated.

The sections are thus made integral, and are generally of continuous repeated S-section. Their length will depend upon the building in which they are to be used, and they may be as long as the height of a two-story dwelling without being too cumbersome or heavy to be handled in erection.

In the field, the sections are erected and assembled as illustrated in Fig. 4. Their adjacent end parts are in hooked relation as before but the sections are adjusted in their general plane to give the desired overall length, which usually in practice leaves an overlap 5. At the overlap, the lips 2 are secured to their underlying parts by self-threading screws 6 driven by hand. The metal of the units is sufficiently thin to permit this, the screws 6 being driven as necessary, making their own perforations in the metal, cutting their own threads as they proceed and holding in the threads against withdrawal. The effect of the overlap of the sections is to provide therebetween, as at 5, a hollow rectangular column in the plane of the wall, running vertically, and adding great rigidity and supporting strength to the wall.

After the wall base is thus completed, the metal is overlaid with boards 7 of stiff composition of heat insulating properties. Many such boards, making use of fibrous by-products, are to be found upon the market. The boards extend horizontally, bridging between the metal faces and closing the channels therebetween.

Fig. 5 illustrates the base with the insulating-board 7 attached thereto. Its manner of attachment is by self-threading screws 8, each screw being driven into the near bottom part 1 of one of the channels of the metal base, the screw cutting and threading its own hole when driven as a nail.

Although the wall board may have little unit strength, yet when the metal base is covered on both sides as in Fig. 5, much strength is added

to the whole since the board amply maintains the webs 3 against buckling. Also, the addition of the board results in a wall base highly resistant to heat transfer. And particularly if the 5 wall board be of fire resistant properties, the metal is protected, and the wall base thus has highly desirable qualities from every point of view.

Where adjacent wall panels are disposed to 10 form corners, it will be found that the adjacent end parts of the panels always define a vertically extending, externally opening recess generally of rectangular section as indicated, Figs. 6, 7 and 8, which illustrate all of the possible 15 relations of the parts at typical exterior corners.

A hollow metal column 9 of square section is disposed in the corner recess and the metal parts secured to the column and thus to each other, preferably as by welding. The column 20 being preferably of seamless steel tubing or the like, its presence adds great strength and rigidity to the metal work. When the insulating-board 7 is attached it is overlaid upon the column both concealing and protecting the latter, 25 as indicated in Fig. 6.

After the wall structure has been covered with insulating-board, suitable finishing means may be applied, such as plaster or paint on the inside surfaces, and metal or masonry sheathing on 30 the outside surfaces, all as will be understood by one familiar with the art.

What I claim is:

1. A metal building wall base section comprising a plurality of similar units, each unit comprising a sheet metal strip bent lengthwise to form wide shallow adjacent channels opening oppositely, with the channel bottom parts defining side faces for the unit, and with lips outwardly extending from the free channel extremities at the opposite edges of the unit, said units 35 being disposed edge to edge in a common general plane, with the lip of one unit overlying the bottom part of the near channel of the next unit, and secured thereto as by welding, whereby the section comprises in effect a continuous repetition 40 of said units, and the side edge parts of the section are those of the end units.

2. A metal building wall base section comprising a plurality of similar units, each unit comprising a sheet metal strip bent lengthwise 50 to form a pair of wide shallow adjacent channels opening oppositely, with the channel bottom parts defining side faces for the unit, and with lips outwardly extending from the free channel extremities at the opposite edges of the unit, said

units being similarly disposed, edge to edge in a common general plane, with the lip of one unit overlying the bottom part of the near channel of the next unit and secured thereto as by welding. 5

3. A metal building wall base including an adjacent pair of sections each composed of similar units, each unit comprising a sheet metal strip bent lengthwise to form wide shallow adjacent channels opening oppositely, with the channel 10 bottom parts defining side faces for the unit, and with lips outwardly extending from the free channel extremities at the opposite edges of the unit, said sections being disposed in a common general plane, with the end lip of one section 15 overlying the bottom part of the near channel of the next section, substantially spaced from both sides of said near channel, and secured to said bottom part of the latter, whereby the adjacent end parts of said sections overlap to form a hollow rectangular column running with the bends of the parts, and located intermediate the ends of said base. 20

4. A metal building wall base including an adjacent pair of sections each composed of similar units, each unit comprising a sheet metal strip bent lengthwise to form wide shallow adjacent channels opening oppositely, with the channel 25 bottom parts defining side faces for the unit, and with lips extending outwardly from the free channel extremities at the opposite side edges of the unit, the units of a section being made integral by welding the intermediate lips of the section to their underlying parts, said sections 30 being disposed in a common general plane, with the end lip of one section overlying the bottom part of the near channel of the next section intermediate the sides of said channel, and self-threading screws securing said end lips with their 35 underlying parts, whereby the sections, of integrally joined units, are adapted to be made up in the shop with welded connections, and joined 40 in the field by threaded connections.

5. In a metal building structure having wall panels comprising sheet metal strips bent lengthwise to form wide shallow adjacent channels opening oppositely, with lips outwardly extending from the free channel extremities at the 45 opposite edges of the units thus formed, a corner construction for an angularly related pair of 50 said panels, comprising a hollow metal column of quadrilateral section seating in the external recess formed by said disposition of the panels and secured to the abutting panel parts.
